UNITED STATES PATENT OFFICE.

OLMEDO C. WYSONG, OF GREENSBORO, NORTH CAROLINA; FANNIE I. WYSONG
EXECUTRIX OF SAID OLMEDO C. WYSONG, DECEASED.

CASE-CLAMP.

1,311,632.

Specification of Letters Patent. Patented July 29, 1919.

Application filed December 10, 1917. Serial No. 206,421.

To all whom it may concern:

Be it known that I, OLMEDO C. Wysong, a citizen of the United States, and a resident of Greensboro, in the county of Guilford 5 and State of North Carolina, have invented a new and useful Improvement in Case-Clamps, of which the following is a specification.

My present invention relates particularly to case clamps, whose general function is to clamp the sections or parts of the frames of articles of furniture in assembled relation, preparatory to the locking of the joints thereof by brads, wooden pins or other 10 means, and for which purpose it is particularly desirable that the assembled parts be held in such manner as to permit of their adjustment as a whole in the assembled relation, in order to conveniently reach 15 each and every corner thereof both inside and outside.

In the construction embodying my invention therefor, a pair of opposing spaced apart platens, the distance between which 20 may be readily adjusted before the application of pressure, are utilized in connection with such supports as permit of their pressure toward one another by power means, under control of the operator, and of their 25 rotation about a coaxial plane irrespective of such pressure.

My invention aims to provide a case clamp which may be readily and quickly adjusted and manipulated in use, in which relatively 30 fine adjustment may be accomplished, and in which the power may be quickly applied and released. My invention further aims to provide a case clamp having power actuated means for applying pressure to the 35 platens and provided with other means, ordinarily acting as an adjusting means, and capable of bringing about the desired pressure of the platens manually.

Various other objects, and the resulting 40 advantages of my invention, will be apparent from the following description of its preferred embodiment, in which my invention in its most specific aspect resides.

In the accompanying drawings which 45 illustrate this preferred form and constitute a part of this specification,

Figure 1 is a front elevation of my improved case clamp complete.

Fig. 2 is a side view looking at the power actuated platen. 55

Fig. 3 is a detail vertical section through the power upright taken substantially on line 3—3 of Fig. 2.

Fig. 4 is a front view of the intermediate portion of the power upright. 60

Fig. 5 is a perspective view of the central portion of the power actuated platen.

Fig. 6 is a perspective view of the parts shown in Fig. 4.

Fig. 7 is a detail perspective view of the 65 lower portion of one of the platens looking at its inner face.

Fig. 8 is a sectional side view of the lower portion of one of the platens looking at its outer face. 70

Fig. 9 is a vertical section through a portion of one of the platens.

Figs. 10 and 11 are detail horizontal sections taken respectively on lines 10—10 and 75 11—11 of Fig. 9.

Fig. 12 is a vertical section through the manual upright.

Fig. 13 is a horizontal section taken substantially on line 13—13 of Fig. 12.

Fig. 14 is a vertical section taken substantially on line 14—14 of Fig. 12. 80

Fig. 15 is a top plan view showing one of the carriages of the manual upright.

Fig. 16 is a transverse vertical section taken substantially on line 16—16 of Fig. 15. 85

Fig. 17 is a sectional view taken substantially on line 17—17 of Fig. 14, and

Fig. 18 is a vertical section through the lower portion of the frame at one end of the case clamp as hereinafter described. 90

Referring now to these figures, the frame of my improved case clamp, which is generally rectangular in form, consists of upper and lower longitudinal parallel beams 20 and 21, the opposite ends of which are connected by vertical beams 22 and 23 so as to form a rigid structure. The lower ends of the upright beams 22 and 23 are secured to the opposite ends of the lower longitudinal beam 21 in connection with pairs of laterally 100 projecting foot blocks 24 and 25 which thus support the entire case clamp in upright position and in such manner that it may be moved from place to place as desired, although it is obvious that I may secure the 105 same permanently in any desired position.

and by any suitable means where such a mounting is either desired or necessary.

The upright beam 22 at one side of the frame is a part of the frame only and inactive in the operation of its parts, while the beam 23 at the opposite ends of the frame forms what I will hereafter denote the power head, in order to distinguish the same from the adjustable manually controlled head 26, the upper and lower ends of which are slideable in connection with the longitudinal beams 20 and 21 so that it may be adjusted toward and away from the power head 23, the latter of which is, of course, stationary at all times.

For this purpose, the longitudinal beams 20 and 21 which may be of the H-shape as shown, or of any other suitable construction, have their lower and upper edges respectively, provided with a longitudinal series of cross slots 27 adapted for engagement by vertically movable latch plates 28 and 29 at the upper and lower ends respectively, of the adjustable head 26. This adjustable head 26 consists of laterally spaced uprights 30 and 31 as best seen in Fig. 14, which are braced in their spaced relation by upper and lower inclined braces 32 bolted through the uprights by bolts 33 and provided at their outer ends with flat faces adjacent the outer edges of the beams 30 and 31 forming seats for the said latch plates 28 and 29 of similar construction, the former of which is plainly to be seen in Fig. 12. Each of these latch plates 28 and 29 has slotted openings 34 through which bolts 35 extend into the respective end of the braces 32, the inner ends of the latch plates 28 and 29 being pivotally connected to the outer ends of vertical connecting rods 36 and 37, the inner ends of which, as seen in Fig. 1, are connected to a lever 38 pivotally mounted upon a stationary portion of the adjustable uprights and manipulation of which serves to simultaneously move the two latch plates 28 and 29 into and out of active position.

Thus, by a comparison of Figs. 1, 12 and 18, the latter of which shows the lower plate 29 in detail, it is obvious that by manipulating the lever 38, to release the latch plates 28 and 29, the adjustable head 26 is freed from the upper and lower frame beams 20 and 21.

The two side uprights 30 and 31 of the adjustable head 26 laps slightly the outer faces of the lower beam 21 and extend upwardly at their upper ends beyond the upper beam 20 and are there connected in a rigid manner, by bolts 39, to a carriage 40 supporting at its opposite ends the axles or shafts 41 as seen in Figs. 12, 15 and 16, in particular, upon which grooved rollers 42 are mounted to engage the upper edges of the upper beam 20 and thus support the adjustable head 26 so that when released as

before described, it may be readily and manually shifted toward and away from the stationary head 23. Each of the platens 43 and 44, the inner faces of which oppose one another in the space between the power head 23 and the adjustable head 26, is carried by one of these heads and in order that they may hereinafter be readily distinguished from one another, I will term the platen 43 as the adjustable platen, and the platen 44 as the power platen. The power platen 44 has a smooth inner face like the platen 43 and may be ribbed as at 45 upon its outer face to strength the same, the ribs radiating from a hub ring 46 within the latter of which is bolted the inner head 47 of its cylindrical plunger 48 as best seen in Fig. 3, the said plunger extending through the cylindrical bore of its bearing box 49, the latter horizontally slideable between upper and lower guides 50 extending between the spaced uprights 51 and 52 of the power head 23 and bolted therethrough by bolts 53. At the outer end of the plunger 48 is bolted a cap 54 engaging the outer end of the boxing 49, and between the inner end of the boxing and the adjacent face of the inner head 47 of the plunger, are disposed bearing rings 55 supporting an annular series of bearing balls 56, by means of which ready rotation of the plunger 48 along with its platen 44 is permitted irrespective of its pressure against the boxing 49.

The boxing 49 has a lower cutout portion as particularly seen in Fig. 3, within which is disposed a link 57, one end being pivotally connected to the boxing at 58, and its opposite end being pivotally connected at 59 to the short upright arm 60 of a bell crank lever fulcrumed upon a cross bolt 61 and the lower downwardly and outwardly inclined arm 62 of which is pivotally connected at its outer end at 63 to the upper end of a piston 64, the latter working vertically in a cylinder 65.

The cylinder 65 is secured between the lower portions of the spaced uprights 51 and 52 of the stationary head 23, and may be bolted through by bolts 66 in the manner shown in Fig. 1. The lower closed end of the cylinder 65 is supplied with fluid, steam, air and the like, through an intake pipe 67 leading to a three-way valve generally seen at 68, having a fluid supply pipe 69 and an exhaust pipe 70 and having a handle 71 by means of which it may be turned to register the cylinder intake pipe 67 with either the fluid supply pipe 69 or the exhaust pipe 70.

It is obvious that when the valve handle 71 is turned to register the valve with the supply pipe 69 and the cylinder intake pipe 67, fluid is supplied into the lower portion of the cylinder which forces the piston 64 upwardly, rocking the bell crank lever and shifting the boxing 46 inwardly by virtue of

the connection of the bell crank lever therewith as previously described, in order to thrust the power platen 44 toward the adjustable platen 43, previous to which the adjustable head 26 has been adjusted with respect to the power head 23 in such manner that when the frame to be clamped is between the platens, just sufficient room is left for the clamping of the parts by such movement of the boxing 49 of the power platen as will permit the bell crank lever 62 to assume a position almost, if not quite, horizontal, inasmuch as the point of greatest power comes at this time.

15 The adjustable platen 43 is constructed similar to the power platen 44 and its outer hub ring 71, as seen in Fig. 12, receives the inner head 72 of its cylindrical outwardly projecting plunger 73, the latter journaled through a slideable boxing 74, inmovable between upper and lower stationary guides 75 and 76 secured, by being bolted through, or otherwise, between the spaced uprights 30 and 31 of the adjustable head 26.

25 As in the case of the power platen, the cylindrical plunger 73 of the adjustable platen 43, has a cap 77 at its outer end to engage the outer end of its boxing 74, between the inner end of which boxing and the head 30 72 of the plunger, are bearing rings 78 supporting an annular series of balls 79 so that the adjustable platen 43 is thus rotatable as freely as the power platen, when desired. It is understood, of course, that when a 35 frame and the like is clamped between the platens, and the latter rotated upon the coincident axes of their plungers, such rotation is simultaneous, as the clamped frame forms a firm connection between the platens, 40 so that control of one of the platens will in operation, effect control of both thereof. To this end, the boxing 74 of the adjustable platen, as seen in Fig. 13, has a laterally offset and longitudinally extending bearing arm 80 in which a latch pin 81 is longitudinally slideable and normally held against the outer face of the hub ring 71 of the platen 43 by means of a spring 82, as seen in Fig. 17, compressed between the inner end of the 45 latch pin 81 and a plug 83 closing one end of the bearing arm 80, said plug having an opening forming a bearing for the handle or stem 84 of the latch pin 81 provided with a gnarled head 85 by means of which the plunger 50 may be manually withdrawn against the tension of the spring 82, should it stick at any time in operation. The outer face of the hub ring 71 of the platen 43 has an annular series of recesses into which the round- 55 ed outer end of the latch pin 81 is movable, the recesses being seen at 86 in Figs. 12 and 13 in particular, so that the two platens with the frame clamped therebetween may be held 60 in various positions against accidental dis-

placement although in such manner that a 65 sudden pull or jerk thereon will serve to displace the latch pin and permit of their rotation.

The boxing 74 of the plunger 73 of the adjustable platen 43 is cutaway at its inner and 70 lower portions to receive the boss 87 of the lower rigid guide 76 of said boxing, which boss has a threaded opening parallel to the axis of the plunger 73, to receive the threaded inner portion 88 of a manual adjusting 75 shaft 89 journaled through a depending portion 90 of the boxing 74 and provided at opposite sides of said depending portion 90 with collars 91 and 92 so as to prevent longitudinal movement of the adjusting shaft 80 with respect to the boxing 74. At its outer end, the shaft 89 has an adjusting wheel 93 so that by manual rotation of this wheel and consequently of the shaft 89, the boxing 74 is adjusted inwardly and outwardly to adjust the platen 43, by virtue of the engagement of the threaded portion 88 of said shaft in the threaded stationary boss 87.

Thus, it is obvious that where more minute adjustment of the adjustable head 26 is 90 desired than can be accomplished by virtue of the latch plates 28 and 29 within the slots 27, such adjustment may be accomplished through the action of the manual adjusting shaft 89, and it is further obvious that 95 should the power connections before described for actuating the power platen 44 fail for any reason, as for instance failure of the source of supply of the operating fluid, the manual adjusting shaft 89 may be utilized to actuate the adjusting platen 43 and provide the necessary power for tightly clamping a frame between the platens in place of the power actuating means of the power platen 44, as previously described. 100

105 Referring now to Figs. 2, 7, 8 and 9, showing the power platen 44 in detail, it is to be borne in mind that in so far as their particular construction is concerned, each of the platens is the counter-part of the other, 110 so that a description of one will suffice for them both.

115 Each of the platens has horizontal transverse bearings 94, one above and one below its axis, for the reception of parallel transverse shafts 95, the extremities of which project beyond the sides of the platens and are squared as seen at 96, said shafts also having bevel gears 97 adjacent their opposite ends in mesh with bevel gears 98 upon 120 the adjacent ends of vertical screw shafts 99 journaled in stationary bearings 100 at the opposite side edges of the platens, these bearings being securely bolted in the platens as seen at 101 in Fig. 7 in particular.

125 The side edges of the platens have vertical ribs 102 with which the grooves of vertically adjustable brackets 103 coact, these

brackets having internally threaded bearings 104 through which the screw shafts 99 extend, so that by the rotation of the latter, the brackets 103 either above or below the horizontal plane of the axis of the platens may be simultaneously adjusted at the opposite sides thereof.

The brackets 103 at the upper and lower portions of the platens are connected in pairs by horizontal beams 105, of dove-tail shape, supporting horizontally adjustable brackets 106 having dove-tail grooves through which the beams 105 extend, these latter brackets 106 being secured in adjusted position by set screws 107, and being flanged to support horizontal frame supporting rails 108, at one end of the latter of which are angular brackets 109 forming stops, the latter also having dove-tail grooves receiving the beams 105 and being secured in adjusted position by set screws 110.

The inner opposing faces of the platens 43 and 44 are divided by vertically and horizontally extended lines 111 and 112, which cross at a point coincident with the axis of its plunger before described, and which lines are blocked off or graduated as shown, in order to form a gage so that by proper adjustment of the upper and lower frame supporting rails 108, the longitudinal axis of the frame to be clamped may be properly aligned with the longitudinal axis of rotation of the two platens 43 and 44, for which purpose the stop brackets 109 coöperate with the other parts so that with the platens adjusted as seen in Fig. 1, the frame A may be shifted between the same and also between the upper row of rails 108 until the stops 109 are encountered.

In order that pressure in use may be prevented from marring or abrading the ends of the frame in the clamped position between the platens, the inner surfaces of the latter are preferably provided with buffer strips 113, secured vertically thereof and in spaced relation, thus preventing the relatively hard surface of the platens from coming directly in contact with the frame being clamped.

By the use of a crank having a squared socket and as seen in dotted lines at 114 in Fig. 9, engaged first with one and then with the other of the shafts 95, it is obvious that the upper and lower rails 108 may be in turn adjusted vertically as desired, the brackets 103 at opposite sides of the platens being simultaneously moved so that there will be no danger of binding during their adjustment. With the rails 108 properly adjusted and the stops 109 properly positioned, it is obvious that with the adjustable head 26 properly positioned with respect to the power head 23, a space is formed 65 into which the frame of the article of fur-

niture being operated upon, may be shifted, the parts of such frames having their dowels or other connections but partly entered into the dowel openings or slots. It may be that the adjustment of the adjustable head 26 70 cannot be accomplished in precisely the desired degree by the coöperation of the latch plates 28 and 29 and the slots 27 of the upper and lower beams 20 and 21, and in this case as before described, the manual adjusting shaft 89 is resorted to. When properly adjusted and when the frame is located as seen in Fig. 1, with its longitudinal axis in the plane of the axes of the plungers 48 and 75 73, it is simply necessary for the operator to 80 adjust the valve 68 as before described, to secure the desired pressure upon the power head 44 so that in its movement toward the adjustable head 43 the parts of the frame will be jammed tightly together and held in 85 such position until the valve is shifted so that the cylinder 65 is exhausted of pressure. In the meantime, with the frame clamped between the platens 43 and 44, it is 90 desired to lock the joints between the parts of the frame by means of either wooden pins through drilled openings or by wired brads and the like, and to do this it is obviously necessary to reach practically every corner of the frame both inside and out, and to 95 avoid inconvenient positions and necessitate the operator running around and around the machine, it is permitted by virtue of the foregoing construction that the two platens 43 and 44 be rotated in unison upon the axes 100 of their plungers so that standing upon one side of the machine, the operator may adjust the platens and conveniently reach each and every part of the frame in clamped position, for the purpose described.

It is furthermore obvious that when this operation has been completed, the frame may be instantly released and withdrawn, and that by virtue of the adjustability of the head 26 as well as the adjustability of the 105 supporting rails 108 of the two platens and of the stops 109, the machine is adapted to a great variety of work, both as to character and size.

It is furthermore obvious that many of the parts, for instance the construction of the upper and lower beams 20 and 21 apart from their slots 27, and the particular constituent parts of the heads 23 and 26, may be modified and varied as desired, without departing in the slightest from the principles here evolved and the terms of the appended claims.

I claim:

1. A case clamp comprising a supporting 125 frame, a pair of supporting heads, one of which is adjustable with respect to the other, a pair of rotatable platens carried by said heads, manually controlled means for adjusting one of said platens in its head to- 130

- ward and away from the other, and power actuated means for moving the other of said platens in its head toward and away from the first-named platen.
- 5 2. A case clamp comprising a supporting frame, a pair of clamping platens mounted in the frame and having supporting means in respect to which they are rotatable and movable toward and away from one another, 10 manual means for moving one of said platens, and power connections engaging one of said platens for forcing the same toward the other platen, for the purpose described.
- 15 3. A case clamp comprising a frame, a pair of normally spaced and vertically disposed clamping platens rotatably mounted in the frame and movable toward and away from one another, each of said platens having vertically adjustable and vertically spaced work supporting rails and having adjustable stops at one end of the said rails movable with the latter.
- 20 4. A case clamp comprising a frame, a pair of supporting heads within said frame, rotatable platens carried by the heads and movable toward and away from one another, one of said heads having a horizontally shiftable boxing rotatably supporting its respective platen, a bell crank lever fulcrumed in the said head and connected at one arm to the said shiftable boxing, a power cylinder having a piston connected to the other end of said bell crank lever, and valved fluid supply means for the said power cylinder, 35 for the purpose described.
- 25 5. A case clamp comprising a frame, a pair of supporting heads within the frame, one of which is stationary and the other of 40 which is adjustable toward and away from the first head, said frame including upper and lower parallel longitudinal beams provided with longitudinal series of cross slots, upper and lower latch plates movably carried by the adjustable head for engagement 45 within the said beam slots, and means for simultaneously adjusting said latch plates into and out of active position.
6. A case clamp comprising a frame, a pair of supporting heads within the frame, 50 one of which is stationary and the other of which is adjustable toward and away from the first head, said frame including upper and lower parallel longitudinal beams provided with longitudinal series of cross slots, 55 upper and lower latch plates movably carried by the adjustable head for engagement within the said beam slots, a lever mounted upon the adjustable head, and connecting rods connecting the said lever with the said 60 latch plates, whereby the latter may be simultaneously moved into and out of active position.
7. A case clamp comprising a frame, a pair of rotatable clamping platens movable 65 toward and away from one another within the frame, a pair of supporting heads carrying the platens and one of which has a 70 slideable boxing, a plunger carried by the respective platen and journaled in the boxing, said head having guides for the boxing, one of which is provided with a threaded opening, a manual adjusting shaft journaled through a portion of the boxing and having 75 a threaded portion extending through the threaded portion of said boxing guide, and a handle for said shaft whereby the respective platen may be manually adjusted toward and away from the other platen.
8. A case clamp comprising a frame including upper and lower parallel beams, a pair of platen supporting heads within the frame, one of which is stationary and the other of which is adjustable, a roller 80 mounted carriage disposed upon the upper longitudinal frame beam and supporting the adjustable head for movement toward and away from the stationary head, means carried by the adjustable head and engaging 85 said upper and lower frame beams to secure the head in adjusted position, rotatable clamping platens carried by the said stationary and adjustable heads, and means for moving said platens toward and away from one another, for the purpose described.

OLMEDO C. WYSONG.
